his Attorney J. P. Thurston

UNITED STATES PATENT OFFICE.

CYRUS R. ROBINSON, OF EAST CONCORD, NEW HAMPSHIRE.

FIRE-HOSE SUPPORT.

SPECIFICATION forming part of Letters Patent No. 425,256, dated April 8, 1890.

Application filed July 1, 1889. Serial No. 316,153. (No model.)

To all whom it may concern:

Be it known that I, CYRUS R. ROBINSON, a citizen of the United States, residing at East Concord, in the county of Merrimac and State of New Hampshire, have invented certain new and useful Improvements in Fire-Hose Supports, of which the following is a specification.

The object of this invention is to provide an improved fire-hose support; and the invention relates, particularly, to the construction of the supporting-rod, its fastenings, and the manner of attaching a line of hose and its coupling thereto.

15 The invention is fully set forth in the following specification and claims and clearly illustrated in the accompanying drawings, forming an inseparable part thereof, of which—

20 Figure 1 represents the figure of a fireman holding my improved apparatus, to which is attached a line of hose and its nozzle, from which a stream of water is represented as discharging. Fig. 2 is an enlarged sectional elevation of the upper portion of my device. Fig. 3 is an enlarged broken section of the lower part of my improved device, showing the adjacent ends of both sections of the supporting-rod in their respective relative positions.

30 Similar reference-letters indicate corresponding parts.

My invention involves the use of a supporting-rod, which for convenience in handling is made in two sections A A'. Upon the upper portion A of said rod is rigidly mounted my improved devices for attaching and handling a hose, comprising top and bottom brackets, respectively, B B', and one or more intermediate brackets, as shown, and rods C, extending from one to another of said brackets and bent at c in a manner to form convenient handles. The top bracket B is provided with ears b, having horizontal slots b', in which to place an ordinary stud p, which is provided at opposite sides of a coupling P. A suitable spring-catch b² is also provided in each of the ears b, which protrudes part way through the slots b', for the purpose of holding the coupling in position, and by beveling the front or outside edge of that portion of said catch which enters said slot, as seen in the drawings, its

movement will be effected automatically by contact with the studs p of the coupling when they enter said slots, and by pulling 55 the button b³ the said coupling may be removed.

Various fastenings may be attached to the bottom bracket B' (and also any which may be placed on the rod A at intermediate 60 points) for securing the hose P' therein. In the drawings straps and buckles D d are shown for the purpose. A hook b⁴ may also be formed upon the bracket B, by means of which the device may be hung upon the 65 rounds of a ladder while a fireman is ascending the same.

Sockets b⁵ b⁶ are formed, respectively, in the upper and lower brackets for the reception of either end of the section A' of the supporting-rod when the said section is not required for a ground-rest, and within the socket b⁵ of the bracket B is arranged a spring-follower F, as shown in Fig. 2, and to place the section A' as seen by dotted lines, 75 Fig. 1, one of its ends is first entered into the socket b⁵ and pressed upward until the lower or opposite end will enter the socket b⁶, where it will remain by force of gravity. That end of said section A' which attaches to the 80 socket b⁷ of the bracket B' is preferably formed conical and provided with an annular groove a for engaging a spring-catch G, which is provided upon the said bracket B', entering the socket b⁷, as shown best in Fig. 85 3, by which means the said section A' of the rod is firmly held in the position shown in full lines, Fig. 1.

Having fully described my invention, what I claim, and desire to secure by Letters Patent, 90 is—

1. In a fire-hose support comprising brackets B B' and connecting handle-bars, as shown, the combination of a supporting-rod formed in two sections, one section being rigidly attached to said brackets and the other forming a detachable extension thereof, substantially for the purpose set forth. 95

2. In a fire-hose support comprising brackets B B' and connecting handle-bars, as shown, the combination of a supporting-rod formed in two sections, one section being rigidly attached to said brackets and the other forming a detachable extension thereof, and means for 100

automatically connecting the said detachable section, substantially as shown and described.

3. The combination of the bracket B, having a socket b^5 and a spring-follower therein, the bracket b' , having the socket b^6 , and the detachable supporting-rod section, all substantially for the purpose set forth.

4. The combination of the bracket B, having a hook, as shown, for engaging the rounds of a ladder, the brackets B' and connecting handle-bars, a supporting-rod formed in two

sections, one section being rigidly connected to said brackets and the other forming a detachable extension thereof, and means for automatically connecting the said detachable section, substantially for the purpose set forth. 15

In testimony whereof I affix my signature in presence of two witnesses.

CYRUS E. ROBINSON.
